UNITED STATES PATENT OFFICE.

RIAL N. DENISON AND FRANK M. GEARY, OF BROOKLYN, NEW YORK.

ANTISEPTIC MOUTHPIECE FOR TELEPHONES.

SPECIFICATION forming part of Letters Patent No. 529,609, dated November 20, 1894.

Application filed April 25, 1894. Serial No. 508,961. (No model.)

To all whom it may concern:

Be it known that we, RIAL N. DENISON and FRANK M. GEARY, of Brooklyn, in the county of Kings and State of New York, have invented 5 a new and Improved Antiseptic Mouthpiece for Telephones or Speaking-Tubes, of which the following is a full, clear, and exact description.

Our invention relates to an antiseptic 10 mouthpiece for telephones and speaking tubes, capable of attachment to any telephone or to any speaking tube, and not materially differing in general appearance from the ordinary mouthpiece.

15 A further object of the invention is to provide a mouthpiece which will be cleanly, and in no manner a conductor of germs, and one which may be durably, simply and economically constructed.

20 The invention consists in the novel construction and combination of the several parts, as will be hereinafter fully set forth, and pointed out in the claims.

Reference is to be had to the accompanying 25 drawings, forming a part of this specification, in which similar letters of reference indicate corresponding parts in both the views.

Figure 1 is a longitudinal vertical section 30 through the improved mouth piece, illustrating it as applied to a telephone; and Fig. 2 is a front elevation thereof.

The mouth piece consists of two shells, an inner shell A and an outer shell B. These two shells are spaced a predetermined distance apart, forming a chamber C, and the shells are made to meet at their outer ends, or the outer end of the chamber C is otherwise closed; and the inner end of the chamber is likewise closed ordinarily by the two 35 shells being brought into engagement at that point. Either the inner or the outer shell, preferably the inner shell, is provided with a neck D, exteriorly threaded in order that it may be screwed into the opening in a telephone over the diaphragm; but the mouthpiece may be otherwise applied if in practice it is found desirable, and when the mouth-

piece is used in connection with speaking tubes, the neck D is usually made longer than illustrated, and with a smooth exterior, but 50 the exterior may be roughened if found necessary.

The chamber C is adapted to contain an antiseptic material E, of any desired character. The said antiseptic material may be in the 55 form of a paper, or it may be in the form of a liquid, in which latter event as shown in Fig. 1, the chamber is made to contain felt or other absorbent material, made to closely hug the exterior of the inner shell, the said absorbent material being saturated with or having applied thereto a liquid absorbent.

The speaker using the tube is given the benefit of the absorbent material employed, by producing in the inner shell A a series of 65 apertures F, through which the odor from the absorbent material may readily escape. Preferably the apertures are grouped together quite closely, and extend practically over the entire inner face of the inner shell. In this 70 manner the air may pass through sundry of the apertures, become impregnated with the antiseptic material, and escape through others of the apertures into the interior of the mouthpiece.

Having thus described our invention, we 75 claim as new and desire to secure by Letters Patent—

1. A mouthpiece for telephones and speaking tubes, containing an antiseptic material 80 and provided with vents leading from the material to the interior of the mouthpiece, substantially as shown and described.

2. A mouthpiece, the same consisting of an inner and an outer shell united to form an 85 intervening chamber, the inner shell being perforated, and an antiseptic material located within said chamber, as and for the purpose set forth.

RIAL N. DENISON.
FRANK M. GEARY.
